US0D1003632S

(12) United States Design Patent (10) Patent No.: US D1,003,632 S
(45) Date of Patent:  Nov. 7, 2023

(54) CUP PLACEMENT MAT

(71) Applicants: David Matthew Pedicini, Phoenix, AZ (US); Bailey James Crawford, Gilbert, AZ (US)

(72) Inventors: David Matthew Pedicini, Phoenix, AZ (US); Bailey James Crawford, Gilbert, AZ (US)

(73) Assignee: David Matthew Pedicini, Phoenix, AZ (US)

() Term: 15 Years

(21) Appl. No.: 29/726,485

(22) Filed: Mar. 3, 2020

(51) LOC (14) Cl. 06-11

(52) U.S. Cl. D6/592; D5/99
USPC

(58) Field of Classification Search

USPC ... D5/1, 2, 3, 4, 7, 27, 43, 44, 47, 51, 53, 54, D5/55, 56, 57, 58, 59, 60, 61, 62, 63, 65, 99; D6/592, 601, 602, 608, 610, 613, 621, 622; D19/1, 5; D20/25, 28, 31; D21/333; D25/138, D25/149, 151; D32/40

(57) CLAIM

The ornamental design for a CUP PLACEMENT MAT as shown and described.

DESCRIPTION

FIG. 1 is a top perspective view of a cup placement mat showing our new design;

FIG. 2 is a left-side view thereof;

FIG. 3 is a top view of the design;

FIG. 4 is a right-side view of the design;

FIG. 5 is a bottom view of the design;

FIG. 6 is a frontal view of the design; and

FIG. 7 is a rear view of the design.

The broken lines depict features of the Cup Placement Mat that form no part of the claimed design.

1 Claim, 7 Drawing Sheets
